AIR CONDITIONING

William H. Lapp, Ames, Iowa

Application December 31, 1931, Serial No. 584,250

7 Claims. (Cl. 257—8)

This invention relates to air conditioning for chambers, houses, industrial plants, dwellings and the like.

While heretofore it has proposed to pass air from the outside of a chamber through channels extending below the earth's surface and into the chamber in order to cool the chamber, the process has been found to be expensive and of little practical value. I have found that by recirculating air, together with a desired amount of fresh air through sub-surface passages to and from a chamber or building, the air being kept in agitated condition within the chamber, an efficient, practical, and inexpensive method of conditioning the air within the chamber is obtained. A proper humidity is obtained by maintaining a predetermined amount of water within the passages so that the air passes in contact with the surface of the water. Automatic means are provided also for raising the temperature of the circulated air to the desired temperature, as well as automatic means for controlling the amount of water surface exposed to the current of recirculating air. Another object is to provide means for agitating the recirculated air and directing its course through the chamber or building. Other objects and advantages will appear as the specification proceeds.

The invention is fully described in the following specification and shown in the accompanying drawings, in which—

Figure 1 is a sectional view of a building or chamber equipped with apparatus embodying my invention, the section being taken as indicated at line 1 of Fig. 2; Fig. 2, a sectional view, the section being taken as indicated at line 2 of Fig. 1; Fig. 3, a diagrammatic detail view of the thermostatically controlled fuel feed valve; Fig. 4, a broken, partially sectional view, the section being taken as indicated at line 4 of Fig. 5; Fig. 5, a sectional view, the section being taken as indicated at line 5 of Fig. 4; and Fig. 6, a detail sectional view, the section being taken as indicated at line 6 of Fig. 4.

In the illustration given, A represents a chamber or building; A', a section of earth upon which building A rests; B, tile or pipe extending from the interior of building A to a certain depth below the surface of the earth A'; and C, fan means for recirculating air to and from the building A through the underground passages B.

The building or chamber A may be of any suitable construction. It is preferred that the doors, windows, etc., with which the building or chamber is equipped, be kept closed, and that the

building be insulated with good insulating material. The tile or pipe B may be of any suitable number, dimensions, and may be laid in any desired way to effect the purpose of the invention.

In the illustration given, the inlet pipes 10 and 11, as shown more clearly in Fig. 2, are substantially in the shape of the letter U. At the central portion near the base 12 of the pipes 10 and 11, a horizontal tile 13 communicates with the inlet pipes. At its other end, the horizontal pipe 13 communicates with a vertical outlet pipe 14 which extends above the floor of the building A and into the fan box 15. Preferably, inlet pipes 10 and 11 are located at the opposite end of the room from outlet pipe 14 and extend some distance above the top of outlet pipe 14 and box 15. The base 12 of inlet pipes 10 and 11 and the horizontal pipe 13 are preferably located about fifteen feet below the earth's surface, at which depth a substantially constant temperature, ranging between 52° to 58°, prevails the year round.

The fan box 15 may be of any suitable construction. As illustrated more clearly in Figs. 4 and 5, it may be a rectangular box closed on all sides except one end, at which end is mounted a fan 16 driven by motor 17. An adjustable baffle or deflector 18 is hingedly connected to the box near the fan and is used to regulate the air currents toward the front wall of building A. In order to heat the incoming air, a heating coil 19 is disposed within the box directly above the mouth of outlet pipe 14. The coil 19 communicates through pipe 19a with another coil 20 in heater 21. A vertical pipe 19b leads from pipe 19a and communicates with a safety expansion chamber 19c. Any suitable means for heating coil 20 may be employed. As illustrated, an oil burner 22 is supported below coil 20 and is supplied with fuel through pipe 23. Preferably, pipe 23 is provided with a coil 24 which is supported within the chamber or building A and adjacent box 15. This coil permits a pre-warming or heating of the fuel on its way to burner 22.

Pipe 23 extends to a suitable fuel supply tank 25 preferably located at an elevated position outside of chamber A. The fuel thus flows by gravity from tank 25 to burner 22. In order to control the flow of fuel through pipe 23, a thermostatically controlled valve 26 is interposed in the line. As shown more clearly in Fig. 3, a valve plunger 27 is operated by a pivoted bar 28 which swings between oppositely disposed magnets 29 and 30. The magnets are energized separately

by a thermostat 31 which is set to maintain a desired temperature within the chamber. Any other suitable means for automatically controlling the feed to maintain the desired temperature within chamber A may be employed.

As heretofore stated, the dimensions or number of tile or pipes B may be adjusted to provide for the volume of air to be recirculated and to the time required to effect a heat exchange between the recirculated air and the underground pipes. In a building twenty feet (20') by twenty feet (20'), a tile or tube of from fifteen inches (15") to thirty inches (30") diameter has been used satisfactorily according to the plan illustrated more clearly in Figs. 1 and 2.

It is preferred to have the inlet pipes of greater dimensions or greater in number than the horizontal pipe or pipes which communicate therewith below the earth's surface because the cooled air occupies less space than the air entering inlet pipes 10 and 11. The number and shape of the pipes will doubtless have to be varied to meet the particular requirements of each building, and will change with variations in other factors of the process, as for example, the speed of recirculation, etc.

In effecting the desired heat exchange in the underground tile, the time element enters, and if the volume of air recirculated is drawn through the tile very rapidly, a greater extent of underground pipe will be required. Any man skilled in the art, however, can compute the amount of tile area required to effect the desired heat exchange for the volume of recirculated air.

In order to bring the recirculated air into the chamber with a proper relative humidity, the air passing through the underground channels B is preferably brought in contact with a pool of water. This pool is preferably maintained in the bottom of horizontal pipe or pipes 13. In ordinary practice, a certain amount of water will seep into the tile and the water level may be maintained by means of pump 32 which communicates with the bottom of tile 13 through pipe 33.

If desired, the tubes B may be made watertight and the necessary amount of water introduced through the inlet pipes 10 and 11. It is preferred, however, to allow water to percolate into pipes 13 and to maintain the level of the water at a certain point by automatic means for controlling pump 32. These means consist preferably of a float 34 which engages the pivoted lever 35. When the level rises too high, the float rises and the outer end of lever 35 makes a contact at 36 which actuates motor 37 and starts the pump 32. Preferably, the float 34 is equipped with a rod 34a which is guided in collars 34b. Collars 34b are secured to pipe 33.

In order to introduce fresh air into pipes B, an inlet pipe 38 is provided which communicates with one or both of the inlet pipes 10 or 11, and extends through the wall of building A. The pipe 38 is provided with a damper 39 and inlet pipes 10 and 11 are also provided with dampers 40 which are preferably disposed just above the point of junction between the inlet pipes and pipe 38.

In the operation of the apparatus, the fan C is started and maintained at the desired speed. Preferably, the fan is driven at a rate which will draw air through the underground channels at about six to eight feet per second. Air from the room or building passes down through inlet pipes 10 and 11 and through the horizontal pipe or pipes 13 and finally up through the vertical pipe 14 into box 15. If it is a warm season, the

heater 22 is not used and the cooled air passes through box 15 and is deflected by the adjustable shield 18 against the front wall of the chamber. In the passage of the air through horizontal pipe 13, it contacts with the top surface of a pool of water, the level of which is regulated by pump 32 and the automatic means controlling the pump. For example, if the level of the pool exceeds the desired level, float 34 is raised, thereby depressing the free end of lever 35 so as to meet contact point 36. As will be seen more clearly in Fig. 1, the circuit in which the motor 37 is located, is completed and the motor is started. After pump 32 has lowered the level of the pool in pipe 13, the float drops and the free end of lever 35 is raised, thus breaking the contact and stopping motor 37.

If the season is cold, and it is desired to raise the temperature of the air passing through pipes B, the heater 22 is used to heat the liquid in coils 20 and the heat is transferred to coil 19 in box 15. Automatic means, in the nature of a thermostat, for controlling the valve 26 in the fuel line 23 are provided. The valve is opened or closed by thermostat 31 which energizes either magnet 29 100 or 30 according to the temperature setting of the thermostat and the temperature prevailing within chamber A. An additional economy in heat may be brought about in cold winter months by introducing fresh air through pipe 38, the temperature of which air is raised say from 20° F. to approximately 52° F. before it reaches the heating coil 19.

If desired, a cooling coil 14a may be used, as illustrated, to cool the air passing through the 110 underground pipes. Brine or other cooling fluid may be circulated from a suitable source of refrigeration through coils 14a. If mechanical cooling or refrigerating apparatus is used, the cost of operation will be reduced to a minimum because 115 of the recirculation operation in which cooled air is recooled.

In cooling the building in the summer time, the recirculation of partially cooled air, rather than the heated air outside of the building, enables 120 the air within the building to be lowered to a comfortable degree in a very short time and at a very small cost. In the winter time, fuel costs are reduced to a minimum because the warm air is reheated. The agitation of the air by fan C 125 and deflector 18 also aids in conditioning the air for the comfort of the occupants of the building. The humidity is maintained at a constant level due to the moisture in the underground tile. With the method described, the temperature variation 130 at any two given points in a room will be the lowest possible.

The process and apparatus have been found particularly useful in connection with poultry laying houses, brooding rooms and feeding stations in which uniform temperature and humidity have been found to be necessary for the successful brooding of chicks and for the production of eggs. The process is, however, just as applicable to other buildings, dwellings, etc. in which inexpensive cooling, heating and conditioning of air is desired.

The foregoing detailed description has been given for clearness of understanding only, and no unnecessary limitations should be understood 145 therefrom, but the appended claims should be construed as broadly as permissible, in view of the prior art.

I claim:

1. In apparatus of the character described, a 150

- chamber, underground pipes having an inlet communicating with said chamber at one end thereof and an outlet communicating with the chamber at the other end of said chamber, a box communicating with said outlet pipe, a power driven fan rotatably mounted in the open end of said box, a heating coil disposed within said box adjacent the outlet of said pipe, an adjustable deflector secured to said box adjacent said fan, and thermostatically controlled heating means for supplying a heating fluid to the coil within said box. 5 with the other end of said chamber, a casing carried by said outlet pipe and affording a fan chamber, a fan mounted in the open end of said chamber, and a deflector adjustably mounted at the open end of said casing chamber. 80
2. In apparatus of the character set forth, a chamber, an underground pipe having a plurality of inlet pipes communicating with one end of said chamber and having an outlet pipe communicating with the other end of said chamber, a box communicating with the outlet pipe and having a power driven fan rotatably mounted in the open end of said box, a deflector adjustably mounted at the open end of said box, and thermostatically controlled heating means adapted to heat the air entering said box. 15 85
3. In apparatus of the character set forth, a chamber, an underground pipe having a plurality of inlet tubes communicating with one end of said chamber and having an outlet pipe communicating with the other end of said chamber, a casing carried by said outlet pipe and affording a fan chamber, a fan mounted in the open end of said chamber, a deflector adjustably mounted at the open end of said casing chamber, and means for heating the air entering said box. 20 90
4. In apparatus of the character set forth, a chamber, an underground pipe having an inlet tube communicating with one end of said chamber and having an outlet pipe communicating with the other end of said chamber, a box 25 95
5. In apparatus of the character set forth, a chamber, an underground pipe having an inlet tube communicating with one end of said chamber and having an outlet pipe communicating with the other end of said chamber, a casing carried by said outlet pipe and affording a fan chamber, a fan mounted in the open end of said chamber, and a deflector adjustably mounted at the open end of said casing chamber, and means for heating the air entering said box. 100
6. In apparatus of the character set forth, a chamber, an underground pipe having an inlet tube communicating with one end of said chamber and having an outlet pipe communicating with the other end of said chamber, a fresh air pipe communicating with said inlet tube and extending through the wall of said chamber, a casing carried by said outlet pipe and affording a fan chamber, a fan mounted in the open end of said chamber, and adjustable means for controlling the flow of return air through said outlet pipe and of fresh air through said fresh air pipe. 105
7. In apparatus of the character set forth, a chamber, an underground pipe having inlet and outlet portions extending into said chamber, a fresh air pipe also communicating with said underground pipe, fan means for drawing air into said chamber through said underground pipe, and an adjustable damper controlling the flow of return air through said inlet pipe. 110
